UNITED STATES PATENT OFFICE

FREDERICK G. WARRELL, OF LANSDOWNE, PENNSYLVANIA, ASSIGNOR TO THE EUELECTRIC CO., A CORPORATION OF NEW JERSEY.

TELEPHONIC TRANSMITTER.

No. 901,570.

Specification of Letters Patent.

Patented Oct. 20, 1908.

Application filed October 3, 1907. Serial No. 395,743.

To all whom it may concern:

Be it known that I, FREDERICK G. WARRELL, a citizen of the United States, residing at Lansdowne, in the county of Delaware, State of Pennsylvania, have invented a new and useful Telephonic Transmitter, of which the following is a specification.

My invention consists of a telephonic transmitter, in which there is a complete conductor from one pole to the other, and there is a high internal resistance, allowing the transmitter to be made of small dimension and dispense with an induction coil for battery purposes, and adapting it to be used for long or short distances with equally good results.

Figure 1 represents a side elevation of a telephonic transmitter embodying my invention. Fig. 2 represents a longitudinal section thereof. Figs. 3 and 4 represent perspective views of detached parts. Fig. 5 represents a side elevation of a modification of a member of the device. Fig. 6 represents a section thereof on line $x-x$.

Similar letters of reference indicate corresponding parts in the figures.

Referring to the drawings:—A designates a shell or casing, on the interior of which is the insulating material B, which extends as a lining around the same, said casing constituting one pole of the transmitter.

C designates an annulus or ring of insulating material, which is located within the shell A and rested against the shoulder D on the said wall of the casing. Connected centrally with said ring is the carbon E, to which is attached the wire or conductor F, which extends therefrom through an opening in the casing A, said carbon constituting the other pole of the transmitter.

The end of the casing opposite to the ring C is primarily open to permit access to the interior thereof, the same being closed by the diaphragm G, which is retained in position by the cap H, the latter being attached to the shell A in any suitable manner. On the back or inner face of said diaphragm G is the carbon J, which is secured thereto in any suitable manner. On the inner face of said diaphragm G is a coating or lining K of insulating material, the same also surrounding the periphery of the carbon J.

Within the chamber formed by the casing A and interposed between the ring C, carbon E, lining K of the diaphragm G and carbon J is a filling L of carbon in granular or pow-

dered condition, whereby the electric current is carried from the carbons or poles E, J through said filling L. It will now be seen that the poles E, J are separated for a considerable distance, but owing to the filling L, with which they are in contact, the current is carried from pole to pole through the filling, and thus there is a high internal resistance, which allows the transmitter to be made of a small size, while at the same time an induction coil is dispensed with, and the transmitter may be used for long as well as short distances.

While I have described the members E, J as carbons, and the filling L as of carbon, it is evident that the same may be formed of other conducting material.

While I have specified certain means for carrying out my improvements, I do not wish to be limited exactly to the same, but desire to make such changes as may come within the scope of the novelty involved, as for instance, in Figs. 5 and 6, the ring or annulus C shown at C in the other figures is provided with a plurality of carbons E', the result in either case being the same.

Having thus described my invention, what I claim as new and desire to secure by Letters Patent, is:—

1. In a telephone transmitter, a diaphragm, a casing, oppositely disposed poles therein, a filling of loose material in the said casing, means for insulating one of said poles and said loose material from said casing, said other pole being secured to said diaphragm, and insulation covering the rear surface of said diaphragm and the periphery of said latter pole.

2. In a telephone transmitter, a diaphragm, a casing, said diaphragm being secured at its periphery to said casing, oppositely disposed poles in said casing, a filling of loose material in said casing, means for insulating one of said poles and said loose material from said casing, said other pole being secured to the center of said diaphragm, and insulation covering the rear surface of said diaphragm and periphery of said latter pole.

3. In a telephone transmitter, a diaphragm, a casing, oppositely disposed poles therein, loose material in said casing forming a complete conductor from pole to pole, means for insulating one of said poles and said loose material from said casing, the other pole being non-insulated from said cas-

ing and secured to the center of said diaphragm and insulation covering the rear surface of said diaphragm and periphery of said last named pole.

5 4. In a telephonic transmitter, a casing, a diaphragm secured thereto, insulation on said diaphragm extending to the outer periphery thereof and having a struck up portion forming a seat, a contact in said seat, a 10 disk of insulating material oppositely disposed to said diaphragm, a contact on said disk and granular carbon in the space between said diaphragm and disk.

5. In a telephonic transmitter, a diaphragm, a casing, oppositely disposed poles 15

therein, loose material in said casing forming a complete conductor from pole to pole, means for insulating one of said poles and said loose material from said casing, said other pole being secured to the center of said 20 diaphragm, and an insulation covering the rear surface of said diaphragm and the periphery of said latter pole, said insulation having a struck up portion forming a seat for the reception of the pole therein.

FREDERICK G. WARRELL.
